CLAIM

The ornamental design for a pizza oven cover, as shown and described.

DESCRIPTION

FIG. 1 is a front, top perspective view of a pizza oven cover, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of section 9 in FIG. 4;

FIG. 10 is an enlarged view of section 10 in FIG. 4; and,

FIG. 11 is an enlarged view of section 11 in FIG. 5.

The dash broken lines in the figures illustrate portions of the pizza oven cover that form no part of the claimed design. The dot dash broken lines in the figures illustrate the boundaries of the enlarged views and form no part of the claimed design.

1 Claim, 11 Drawing Sheets
